No. 625,378.

Patented May 23, 1899.

S. H. BURKHART & A. KUNKEL.
AUTOMATIC FIRE AND BURGLAR ALARM.

(Application filed Dec. 18, 1898.)

(No Model.)

UNITED STATES PATENT OFFICE.

SAMUEL H. BURKHART AND AUGUST KUNKEL, OF JOHNSTOWN, PENNSYLVANIA.

AUTOMATIC FIRE AND BURGLAR ALARM.

SPECIFICATION forming part of Letters Patent No. 625,378, dated May 23, 1899.

Application filed December 13, 1898. Serial No. 699,166. (No model.)

To all whom it may concern:

Be it known that we, SAMUEL H. BURKHART and AUGUST KUNKEL, citizens of the United States, residing at Johnstown, in the county 5 of Cambria and State of Pennsylvania, have invented a new and useful Automatic Fire and Burglar Alarm, of which the following is a specification.

The invention relates to improvements in 10 automatic fire and burglar alarms.

The object of the present invention is to improve the construction of burglar and fire alarms and to provide a simple, inexpensive, and efficient device which will be positive 15 and reliable in operation and capable of automatically ringing a bell in case of fire or an attempt to enter a house surreptitiously.

The invention consists in the construction and novel combination and arrangement of 20 parts hereinafter fully described, illustrated in the accompanying drawings, and pointed out in the claims hereto appended.

In the drawings, Figure 1 is an elevation illustrating the manner of applying the device 25 to a window. Fig. 2 is a plan view of the circuit-closing device, the top plate of the casing being removed. Fig. 3 is a transverse sectional view. Fig. 4 is a detail perspective view of the contact-plate. Fig. 5 is a similar 30 view of the spring. Fig. 6 is a sectional view of the circuit-closing device, illustrating the arrangement of parts for use as a fire-alarm.

Like numerals of reference designate corresponding parts in all the figures of the drawings.

1 designates a substantially rectangular casing provided at its ends with projecting segmental flanges and having a removable face-plate 3, which is supported above the 35 back of the casing by sides 4 and ends 5, preferably formed integral with the back 6. The segmental flanges are provided with perforations adapted to receive screws 7 or other suitable fastening devices for securing the 40 casing to a suitable support. Within the casing is arranged a substantially U-shaped spring 8, composed of sides 9 and 10 and a connecting-coil 11, located at the bottom of the casing and receiving a screw 12 for securing 45 the spring to the back. The side 9 of the spring is slightly curved and extends through

the upper end or top of the bracket to a binding-post 13, which is connected with the bell-wire 14 of a circuit 15, and the top of the casing is provided with an aperture through 55 which the spring projects. The projecting end of the spring is coiled around the binding-post or arranged in any other suitable manner to make the proper contact. The other side 10 of the spring is arranged between 60 a pair of contact-points 16 of a plate 17, which is connected with a binding-post 18, and the latter receives the battery-wire 19 of the circuit 15. The circuit extends to a bell 20 and a battery 21, and when the side 10 of the 65 spring contacts with either of the points 16 the circuit is closed and the bell rung.

The plate 17 extends through an aperture 22 of the upper end of the casing, and its lower portion is bifurcated to form a pair of arms 70 23, which have their ends upturned to provide the contact-points 16, between which the side 10 of the spring is arranged. The side 10 of the spring is provided near its upper end with a bend 24, which is linked into a 75 perforation or eye of a link or bar 25, which is provided at its outer end with an eye 26. The link or bar, which extends through a slot 27 of the adjacent side of the casing, is designed to be connected with a cord 28 or other 80 similar connection adapted to be readily broken or burned to permit the spring to expand and close the circuit. The link or bar 25 may be omitted, and the cord 28 is then attached directly to the arm 10 of the spring. 85 This construction is particularly desirable when the device is used only as a fire-alarm; but instead of employing a bar or cord any other suitable connection may be used for holding the arm 10 of the spring normally out 90 of engagement with the contact-points.

The device may be arranged, as shown in Fig. 1 of the accompanying drawings, to provide a burglar-alarm, and the cord 28 is connected with a curtain 29. When the cord is 95 taut, the arm 10 of the spring is arranged between the contact-points 16 and away from the same, as illustrated in Fig. 2 of the accompanying drawings, and should the cord be pulled or broken the arm 10 will close the 100 circuit and sound an alarm automatically. If the curtain should be pushed inward or

drawn outward, the cord 28 will be pulled sufficiently to carry the arm 10 into contact with one of the points 16, and should the cord break the resiliency of the spring will carry 5 the arm 10 into contact with the other point.

- The casing is provided at its corners with triangular projections 30, adapted to support a cord 31 and hold the same beyond the sides of the casing, as clearly illustrated in Fig. 5 10 of the accompanying drawings. The continuous cord 31, which passes around the exterior of the casing, passes through the perforation 32 of the link or bar 25 and is adapted to hold the side 10 of the spring out of engagement with the contact-points, and should 15 a fire break out in the vicinity of the device the cord 31 will be burned, thereby releasing the arm 10 of the spring and permitting the same to close the circuit.
- 20 A cord may be arranged around windows and doors to provide a burglar-alarm, and it can be located adjacent to stoves, flues, and other parts liable to catch afire, and should a fire break out the cord will be partially destroyed, whereby the arm 10 of the spring 25 will be released and the circuit closed.

The invention has the following advantages: The device, which is exceedingly simple and inexpensive in construction, is positive and 30 reliable in operation and is capable of forming an effective fire and burglar alarm. The arm 10 of the spring is adapted to close the circuit whether the cord or connection is broken or pulled upon, and the said cord or 35 connection may be readily arranged at windows and doors and in localities liable to catch afire.

Changes in the form, proportion, and minor details of construction may be resorted to 40 without departing from the spirit or sacrificing any of the advantages of this invention.

What is claimed is—

1. A device of the class described comprising a casing having a pair of binding-posts designed to be connected with the wires of a circuit and located on the exterior of the casing, 45 a plate connected with one of the binding posts and extending into the casing, the inner portion of the plate being bifurcated and 50 forming a pair of arms, and a substantially U-shaped spring having one side connected to the other binding-post, the other side of the spring being arranged between the arms of said plate, substantially as and for the purpose described. 55

2. A device of the class described comprising a casing having a pair of exteriorly-arranged binding-posts, a plate connected with one of the binding-posts and extending into the casing, said plate having a pair of interiorly-arranged contact-points, an interiorly-arranged spring having one end disposed between the contact-points and connected, at its other end with the binding-post, and a link connected to the spring and extending 60 through the casing, substantially as described. 65

3. A device of the class described comprising a casing, contact-points arranged within the same, a circuit-closing device housed within the casing and adapted to be thrown 70 into contact with one of the points by spring action, and a cord extending around the casing and connected with the circuit-closing device and normally holding the same between the contact-points, said cord being adapted 75 to be burned to release the said circuit-closing device, substantially as described.

4. A device of the class described comprising a casing provided with projections, a pair of contact-points mounted within the casing, 80 a circuit-closing device arranged between the contact-points and adapted to be thrown by spring action against one of them, and a continuous cord arranged on the said projections and connected with the circuit-closing device 85 to hold the same normally away from the contact-points, substantially as described.

5. A device of the class described comprising a casing provided with projections, a pair of contact-points mounted within the casing, 90 means for connecting the same with one of the wires of a circuit, a spring designed to be connected with the other wire of the circuit and arranged between the contact-points and adapted to be thrown against one of the same 95 by its resiliency, a link connected with the spring and extending through the casing, and a continuous cord arranged on the said projections and engaging the link, to hold the spring normally away from the contact-points, substantially as described. 100

In testimony that we claim the foregoing as our own we have hereto affixed our signatures in the presence of two witnesses.

SAMUEL H. BURKHART.
AUGUST KUNKEL.
